SHOE STRETCHER

John A. Kaley, Elyria, Ohio

Application November 9, 1932, Serial No. 641,889

11 Claims. (Cl. 12—129.2)

This invention relates to shoe stretchers and more particularly to a device for stretching only that limited portion of the shoe which hurts the foot.

5 An object of the invention is the provision of a shoe stretcher that will produce a slight bulge in a shoe adjacent a corn or bunion while not affecting the remainder of the shoe.

10 Another object is the provision of a device in which the contacting surface of the lever may be positioned to engage with any desired portion of the shoe.

15 Another object is the provision of a shoe stretcher having a pivotal mounting for the clamping elements to accommodate them to the various positionings of the lever.

20 A further object of the invention is the provision of a lever which may be used as a dauber to apply liquid to the interior of the shoe.

25 Other objects will appear from the following disclosure.

In the accompanying drawing

Fig. 1 is a perspective of the assembled shoe stretcher.

30 Fig. 2 is a plan view of the lever removed from the device and showing an attached liquid applying pad.

The base of the device comprises the plates 4 and 5 which have a face-to-face sliding contact 35 permitted by the pivot pin 6 passing through apertures adjacent corresponding ends of the two plates. Preferably the lower plate 5 is provided with an upstanding retaining screw 8 projecting through the arcuate slot 9 of the upper plate.

35 The wing nut 10 on the screw 8 may be used to clamp the plates securely together to prevent their relative motion.

The upper plate 4 has the general contour of 40 the sole of a shoe and is sufficiently reduced in size to permit it to be placed within an ordinary small shoe. The forward part of the under plate conforms to the shape of the forward portion of the upper plate, while the heel portion of the lower plate has been reduced in width to provide

45 only a narrow strip 7 extending to the pivot pin 6. Preferably the upper plate is made of heavy material to withstand the stresses imposed upon it while the under plate may be of relatively thin material so that a comparatively flat under surface results.

To present a large contacting surface with the interior wall of the shoe the outer margin of the under plate is turned up as at 11 and the upper 50 plate is provided with a peripheral flange 12

which may be omitted at that portion adjacent the flange 11.

Projecting upwardly from the central portion of the base plate 4 is a fulcrum post 13 having apertures 14 arranged one above the other. At 60 the heel portion of the plate 4 is an upstanding clamping post 15 having similarly arranged apertures 16. It is desirable that the axes of the upper apertures be coincident, and that the axes of the lower apertures be coincident, as will hereinafter appear. As here shown, these posts are bent up portions of the upper plate 4 which have been partially cut out of that plate. It is apparent that these posts may be provided in any other suitable manner, but the construction shown has 65 the advantage of light weight and is readily formed.

Fulcrumed within one of the apertures 14 is the lever 18, the central part of which is curved as shown in Fig. 2. The lever has a loose fit within the apertures 14 so that it may have free angular motion and rotational motion therein. Either one of the openings 14 may be used, depending on the size of the shoe being stretched and the elevation of the lever that is required. The inner 75 end of the lever is apertured as at 19 and the free end is provided with a relatively enlarged convex surface 20, to engage with the interior of a shoe at the point where stretching is required. This provision of a convex surface which produces a bulge at a limited area is an important 80 feature of the invention since it stretches the shoe only where it hurts the foot and the remaining shape and appearance of the shoe is unchanged.

To cause angular motion of the lever and move 90 the convex surface at its free end into engagement with the shoe, the clamping elements consisting of nuts 21 and 21' and the bolt 24 are provided. The nuts 21 and 21' are provided with pins 22 and 23 respectively, which are mounted within 95 the apertures 16 in the clamping post 15, and are retained therein by cross pins as 25 at their free ends. To prevent interference between the two nuts it is desirable that they project from opposite faces of the post 15, as shown. The bolt 24 100 may be passed through either of the openings 19 at the end of the lever and be screwed into either of the nuts 21, 21'. To facilitate turning the bolt, it is provided with a winged head 26.

The pivotal mounting of the nuts 21 and 21' 105 permits the bolt 24 and the cooperating end of the lever 18 to have a swinging motion when the lever is rotated within one of the apertures 14. When the lever is located in the upper one of the apertures 14 and the bolt is screwed into the upper 110

nut 21, the lever may be rotated freely to any desired position since these axes are coextensive as has been pointed out. That is, the plane defined by the lever and the bolt may rotate about an axis through the upper one of the apertures 14 and 16, irrespective of the extent that the bolt 24 is screwed into the nut 21, since the upper apertures are in line.

The same condition is true when the lever is mounted in the lower aperture 14 and the bolt is screwed into the lower nut 21', since these pivot axes are in line. Angular adjustment of the plane in which the lever lies is not affected by variation in the length of the bolt 24 between the nut 21' and the lever.

It is to be understood, however, that the invention is not limited to the simultaneous use of the axially coincident apertures, but that either upper aperture may be used with a lower aperture as desired, or as most suitable for the particular shoe being stretched.

In using the device the plates 4 and 5 are separated sufficiently to grip the interior of the sides of the shoe, after which the nut 10 is tightened. The location of the lever within the upper or lower aperture 14 and the corresponding connection between the bolt 24 and the nut 21 or 21' is determined by the size of the shoe and the extent to which the surface 20 must be moved outwardly. The convex surface 20 may be placed against the point of the shoe to be stretched, as permitted by the rotation of the lever and the pivoting of the nut, after which the bolt 24 may be screwed inwardly to force the surface 20 against the interior of the shoe.

An additional feature of this invention lies in the utility of the device for applying liquid such as water at the point on the interior of the shoe where stretching is to occur. As shown in Fig. 2, a pad or sponge 27 may be secured to the convex surface by a thread passing through the holes 28. The device with the lever and pad attached are placed within the shoe, as during the stretching operation just described, and the pad is forced into contact with the desired portion of the shoe. It may be allowed to remain until this portion of the shoe has become thoroughly soaked and during this time the outer surface of this portion of the shoe may be soaked by hand with a second pad or sponge (not shown).

It will be apparent that the lever can be separately used as a dauber to apply liquid to the interior of the shoe. With the lever removed from the device and the pad or sponge 27 applied, the lever may be grasped in the hand and its length enables the user to apply the liquid to a remote portion of the interior of the shoe.

What is claimed is:

1. In a shoe stretcher, a base, a lever, means for supporting the lever above the base permitting angular and rotational movement of the lever, and means for causing relative motion between one end of the lever and the base to move the free end of the lever into engagement with the interior of a shoe.

2. In a shoe stretcher, a base plate, an upstanding fulcrum post, a lever loosely mounted within an aperture of the fulcrum post to permit angular and rotational movement of the lever, and clamping means for causing relative motion between one end of the lever and the base plate to move the free end of the lever into engagement with the interior of a shoe.

3. In a shoe stretcher, a base plate, a lever, means for supporting the lever above the base

plate permitting angular and rotational movement of the lever, and clamping means between the base and one end of the lever to move the free end of the lever into contact with the interior of a shoe, said clamping means having a pivotal mounting carried by the base.

4. In a shoe stretcher, a base plate, a lever, means for supporting the lever above the base plate permitting angular and rotational movement of the lever, an upstanding clamping post, and clamping means comprising bolt and nut elements, one of which has a pivotal connection with the clamping post, said clamping means serving to cause relative motion between one end of the lever and the clamping post to move the free end of the lever into engagement with the interior of a shoe.

5. In a shoe stretcher, a base plate, a lever, an upstanding fulcrum post supporting the lever above the base and permitting angular and rotational movement of the lever, an upstanding clamping post, and clamping means for causing relative motion between one end of the lever and the clamping post to move the free end of a lever into engagement with the interior of a shoe, said clamping means having a pivotal connection with the clamping post.

6. In a shoe stretcher, a base plate, an upstanding apertured fulcrum post, an upstanding apertured clamping post, a lever fulcrumed within the aperture of the fulcrum post and being rotatable therein, and clamping means between one end of the lever and the clamping post comprising nut and bolt elements, one of said elements having a projecting pin mounted within the aperture of the clamping post to permit pivotal movement of that element, said clamping means serving to cause relative movement between said end of the lever and the clamping post to move the free end of the lever into engagement with the interior of a shoe.

7. In a shoe stretcher, a base plate, a lever, means for supporting the lever above the base plate, connecting means between the lever and the supporting means permitting angular and axial rotational movement of the lever, and clamping means between the base plate and one end of the lever comprising nut and bolt elements, one of said elements having a pivotal connection with the base plate, the axis of said pivotal connection being substantially coincident with the axis of the connecting means between the lever and the supporting means, said clamping means causing relative movement between the said end of the lever and the base plate to move the free end of the lever into contacting engagement with the interior of a shoe, and said connecting means and said pivotal connection permitting angular adjustment of the plane of movement of the free end of the lever.

8. In a shoe stretcher, a base plate, an upstanding apertured fulcrum post, an upstanding apertured clamping post, the axes of said apertures being substantially coincident, a lever loosely mounted within the aperture of the fulcrum post to have angular and rotational movement therein, and clamping means between one end of the lever and the clamping post, comprising nut and bolt elements, one of said elements being provided with a projecting pin mounted within the aperture of the clamping post to permit pivotal movement of that element, said clamping means causing relative movement between said end of the lever and the clamping post to move the free end of the lever into contacting engagement with the

interior of a shoe, the coincidence of the axes permitting angular adjustment of the plane of movement of the free end of the lever.

9. In a shoe stretcher, a base, a lever, means for supporting the lever at various heights above the base and permitting angular and rotational movement of the lever, clamping means for causing relative motion between one end of the lever and the base to move the free end of the lever into engagement with the interior of the shoe, and means for supporting said clamping means at various heights above the base to correspond with the positioning of the lever.

10. In a shoe stretcher, a base to lie flat against the inner sole of a shoe and comprising a pair of superposed plates pivotally connected whereby they may be laterally adjusted to contact with the upper, retaining means for securing the plates

in fixed relative position, and means for engagement with part of the shoe upper to be stretched, comprising a lever fulcrumed to one of the base plates and clamping means for causing pivotal movement of the lever.

11. In a shoe stretcher, a base comprising plates having an opposed face relation, a pin adjacent corresponding ends of said plates to pivotally connect them whereby they may be adjusted to the lateral width of the interior of a shoe, and a retaining screw at the opposite end of one of the plates and registering with a slot in the other plate to secure the plates in fixed relative position, and means for engagement with the part of the shoe to be stretched comprising a lever fulcrumed to one of the base plates and clamping means for causing pivotal movement of the lever.
